US0D1030961S

(12) **United States Design Patent** (10) **Patent No.:** **US D1,030,961 S**
(45) **Date of Patent:** **** Jun. 11, 2024**

(54) **RECHARGEABLE MISTING FAN**

(71) Applicants: **Robert Vasquez**, Gilbert, AZ (US);
Brian Freeland, Chandler, AZ (US)

(72) Inventors: **Robert Vasquez**, Gilbert, AZ (US);
Brian Freeland, Chandler, AZ (US)

(**) Term: **15 Years**

(21) Appl. No.: **29/831,024**

(22) Filed: **Mar. 17, 2022**

(51) **LOC (14) Cl.** **23-04**

(52) **U.S. Cl.**

(57) **CLAIM**

The ornamental design for a rechargeable misting fan, as shown and described.

DESCRIPTION

FIG. 1 is a front top right side perspective view for a rechargeable misting fan, showing our new design; FIG. 2 is a front elevational view of FIG. 1 thereof; FIG. 3 is a rear elevational view of FIG. 1 thereof; FIG. 4 is a left side elevational view of FIG. 1 thereof; FIG. 5 is a right side elevational view of FIG. 1 thereof; and, FIG. 6 is a top plan view of FIG. 1 thereof. The broken lines indicate unclaimed portions of the rechargeable misting fan and form no part of the claimed design.

1 Claim, 6 Drawing Sheets
